UNITED STATES PATENT OFFICE.

HURXTHAL FIELD FREASE, OF CANTON, OHIO.

STRUCTURAL MATERIAL.

Application filed August 28, 1923. Serial No. 659,716.

To all whom it may concern:

Be it known that I, HURXTHAL FIELD FREASE, a citizen of the United States, residing at Canton, in the county of Stark and State of Ohio, have invented new and useful Improvements in Structural Materials, of which the following is a specification.

My invention relates to structural materials of continuous truss formation; and the object of the improvement is to provide a structural material of continuous truss formation which may be easily made from sheet stock.

A further object of my invention is to provide from sheet stock a structural material of continuous truss formation which may withstand stresses in any direction.

Sheet products now available such as metal lath are apparently of truss formation but are not in the strict sense of the word structural materials because their function as stress members, if any, is only secondary. These products are designed primarily for such purposes as retaining plaster on walls. They have been used to take stress in one direction; namely, as tension members in concrete reinforcing; but their use as main structural members is strictly limited. The commercial expanded metal sheets, while having length and breadth, have not sufficient depth to provide the necessary inherent strength and rigidity to withstand stresses from any direction. The present invention overcomes this difficulty.

Another object of my invention is to provide from narrow gauge sheet stock a structural material of continuous truss formation which has truss elements of substantial length as well as depth. In ordinary expanded metal an increase in the length of truss elements such as the strands requires an increase in the gauge of the sheet stock in order to maintain sufficient cross-sectional dimensions of each individual strand to avoid failure by buckling. This fact not only increases the weight of the resulting sheet of expanded metal, but requires the loss of the more desirable tensile properties of narrow gauge sheets, and also increases the required power of the fabricating machines. The present invention provides a continuous truss formation having any desired length of element from any desired gauge of sheet stock.

Another object of my invention is to provide from narrow gauge sheet stock a structural material of continuous truss formation which may be easily made entirely by manual operations. One of the deterrents to a greater variety of applications of metal lath to structural uses other than mere plaster carrying or concrete reinforcing lies in the fact that an expensive machine is required for making each particular mesh shape and dimensions. It is difficult if not impossible to provide ordinary metal lath having dimensions of mesh, strands, and bonds of any other than that fixed by the conditions of operation of the comparatively few expanded metal fabricating machines. Still another objection to ordinary metal lath as a structural material is that no variety of metallic base is practically possible. Ordinary metal lath fabricating machines are designed to receive a sheet steel stock having particular elastic properties. If it were desired to use sheet stock of another material such as duralumin, serious difficulties would be encountered in adapting the present machines to the new stock. The present invention provides a structural material of continuous truss formation which may be and has been accurately and satisfactorily made by hand from sheet stocks of a variety of metals.

Another object of my invention is to provide from narrow gauge sheet stock a structural material of continuous truss formation which has bonds and strands of dimensions sufficient for positive connection with other structural materials by means of rivets, eyelets, or the like.

In aircraft construction in particular, it is a requirement of United States Government specifications that members taking tension loads shall be joined together by positive fastenings. It has been found inconvenient to meet these specifications by the use of ordinary metal lath. The present invention has bond and strand dimensions which are adapted for positive fastening to other structural elements.

Still another object of the present invention is to provide a material which may be used as a continuous web in built up girder construction. Ordinary metal lath is not adapted by weight or mesh characteristics to such use. The present invention has been

applied with satisfactory results to such a structural use. Duralumin girders were constructed having flange members joined to a continuous web member made according to the present disclosure.

A preferred embodiment of the invention and various applications of its uses are illustrated in the accompanying drawings forming part hereof, in which—

- 10 Figure 1 is a top plan of the structural material showing fixing members in place; Fig. 2, an end elevation of the same; Fig. 3, a side elevation of the same; Fig. 4, a top plan view of a slit sheet blank show-folding lines; Fig. 5, a top plan view of a folded slit sheet blank; Fig. 6, an end elevation of the same; Fig. 7, a top plan view of the application 20 of the invention to an internally braced airplane wing; Fig. 8, a view showing the method of fastening the airplane rib to the material of the present invention; Fig. 9, a view of the rib alone; Fig. 10, a fragmentary cross-section along line X—X; Fig. 11, a view of the fastening strip before folding; Fig. 12, a view of a built-up girder having an integral web construction made possible by the present invention; Figs. 13, 14, and 15, are views of various strand cross-sections; and Fig. 16 is a side elevation of a variation in strand construction.

Similar numerals refer to similar parts throughout the drawings. An understanding of the invention may best be attained by first following through a method of making the structural material of the present disclosure.

In Fig. 4, a sheet blank 1 has been provided with a plurality of slits 2 and bonds 3 alternating with each other lengthwise and crosswise of the sheet. Longitudinal folding lines 4 are shown between longitudinal rows of bonds and slits. In the drawing longitudinal rows of bonds and slits, and 45 of folding lines are shown parallel with each other; and the folding lines are shown midway between the rows of bonds and slits. Neither of these details are essential. The longitudinal bonds and slits, and folding 50 lines may converge; and the folding lines may be displaced at unequal distances from the longitudinal lines of bonds and slits.

In Fig. 5, the same sheet blank is shown after it has been folded alternately along 60 the folding lines and the longitudinal lines of bonds and strands, thus pleating the sheet blank as shown more clearly in Fig. 6, and providing a new formation having a substantial depth as well as a substantial length 65 and breadth, as distinguished from the orig-

inal sheet which had only a substantial length and breadth, and very slight depth, slight depth being one of the essential characteristics of sheet metal.

The formation shown in Figs. 5 and 6, 70 may now be considered to be made up of a plurality of continuous laterally folded strands 5 and bonds 3 joining adjacent strands.

A lateral separation of the bonds 3 of the formation shown in Figs. 5 and 6, will produce the continuous truss formation of the present invention shown in detail in Figs. 1, 2, and 3; and in application in Figs. 7, 80 8, 9, 10 and 12.

Fig. 13 is a cross-section of any of the strands 5 of the embodiment of the invention illustrated in Figs. 1, 2, 3, 5, and 6. Figs. 14 and 15 are cross-sections of two of the many different ways in which strip strands 85 may be formed to increase their beam strength, which are readily produced by slight variations in the above described method of producing the structural material of the present invention. These cross-sections bring out one of the important objects of the invention: that is, to provide for long strands in a continuous sheet truss formation by having strands of typical and variable beam cross-section. 90

It is readily seen that the continuous truss formation is made more strong and rigid by the insertion of longitudinal fixing members 6 in the bond channels 7 of bonds 3 and fastening the bonds to the fixing members by welding or otherwise. 95

Likewise crosswise fixing members might be employed. Fig. 7 shows a partially built-up airplane wing structure where the integral truss formation of bonds 3 and beam-strands 5 have been combined with longitudinal fixing members or spars 6 and ribs 8. Fig. 8 is an end view of a completed wing structure, and Fig. 10 shows more clearly the method of fastening the bonds 3 in the notches 9 of the ribs 8 by means of the folding cover strip 10. 100

The girder 11 shown in Fig. 12, is another application of the structural material of the present invention to practical use. Here longitudinal flange members 12 have been joined to an integral web made up of beam-strands 5 and bonds 3, the bonds having been subject where required to a hinge-like unfolding at 13. It is obvious that a girder 115 having any number of longitudinal flange members 12 and but one integral web made up of beam-strands 5 and bonds 3 may be constructed by the use of the continuous truss formation of the present invention. 120

Fig. 16 illustrates a method of reinforcing the strands of the present invention by means of eyelets 14 which fasten the strand folds to each other, and resist their unfolding. 125 130

It is to be understood that while the drawings show each strand having a single fold, any number of folds may be employed, and all strands need not be made up of the same 5 number of folds.

Moreover, while the bonds in the drawings are shown equally spaced from each other in the same and alternate longitudinal rows, unequally spaced bonds may be employed.

10 I claim:

1. A structural material including a plurality of continuous laterally folded strands and spaced bonds joining adjacent strands.

15 2. A structural material including a plurality of continuous laterally folded strands and spaced bonds integrally joining the edges of adjacent strands.

20 3. A rigid web formation including a plurality of continuous elements each having a formed strip cross-section of substantial width and depth, adjacent elements being joined at intervals.

25 4. A rigid web formation including a plurality of continuous elements each having a formed strip cross-section of substantial width and depth, adjacent elements being

integrally joined at intervals without stretching.

5. A structural material including a plurality of strands and spaced bonds joining 30 adjacent strands, some of the strands and intervening bonds having a plurality of continuous lateral folds.

6. A structural material including a plurality of strands and spaced bonds joining 35 adjacent strands, some of the strands having a plurality of continuous lateral folds, and there being means reinforcing the strand folds.

7. A structural material including a plurality of strands and spaced bonds joining 40 adjacent strands, some of the strands having a plurality of continuous lateral folds, and there being means fastening the strand folds to each other.

45 8. A structural material including a plurality of strands and spaced bonds joining adjacent strands, some of the strands having a plurality of continuous lateral folds, and there being means resisting the unfolding 50 of the folds.

HURXTHAL FIELD FREASE.
